UNITED STATES PATENT OFFICE.

NICHOLAS P. THEOFILOS, OF CHICAGO, ILLINOIS.

AUTOMATIC RAILWAY GATE AND SIGNAL APPARATUS.

1,401,375.

Specification of Letters Patent. Patented Dec. 27, 1921.

Application filed December 24, 1919. Serial No. 347,126.

To all whom it may concern:

Be it known that I, NICHOLAS P. THEOFILOS, a citizen of the United States, residing at Chicago, in the county of Cook and State of Illinois, have invented certain new and useful Improvements in an Automatic Railway Gate and Signal Apparatus, of which the following is a specification.

This invention relates to improvements in automatically operated railway gates and signal devices of the type disclosed in my co-pending application Serial No. 347,125, filed December 24, 1919, and has for its object to provide an improved car carried circuit controlling mechanism particularly designed for use in connection with electric railways, although not necessarily limited to such use.

A further object is the provision of an apparatus of this character wherein conductors interposed in the gate and signal actuating circuits are arranged contiguous to the railway track and are directly engaged by car carried devices whereby to close said circuits and actuate the devices as the car reaches a predetermined point in its approach to the road or highway crossing the railway.

With these and other objects in view as will appear as the description proceeds the invention comprises the novel features of construction, combination of elements and arrangement of parts which will be more fully described in the following specification and set forth with particularity in the claim appended hereto.

Figure 1 represents a diagrammatical view of a section of an electric railway illustrating the invention applied to use.

Fig. 2 represents a fragmental side elevation of a railroad illustrating a modification of the invention.

Referring to the drawing in detail wherein similar reference numerals designate corresponding parts throughout the several views and having particular reference to the construction disclosed in Fig. 1, the numerals 5 and 6 indicate the rails of a double track of an electric railway equipped with the usual overhead trolley wire or conductors 7 and 8 adequately supported from the hanger arms of poles 9. 10 indicates an electrically operated railway car provided with the usual trolley arm 11 carrying the wheel engageable with the trolley wires 7 and 8, according to the direction of travel of the car. The rail-

way car 10 is provided with the usual propelling motor 12 having the ground connection 13 with one of the wheels of the car and having its opposite pole connected with the trolley wheel through a conductor 14, a preferred type of rheostat being preferably interposed between the motor and the trolley wheel for producing such variations in the current as will control the rate of speed of the car.

At the point of intersection of the railway with a road or highway, the usual pivoted gates 15 are arranged as a measure of protection to traffic. The present invention contemplates the automatic operation of the railway gates by a motor 16 which is operatively connected with the gates in the manner suggested in my co-pending application Serial Number 347,125, filed December 24, 1919. An electric bell or other type of signal device designated generally by the numeral 17 is arranged at a point adjacent to the crossing for giving audible signal at the approach of a car. The bell is of a compound type being provided with the usual vibrating clapper 18 having an armature 19 connected with its opposite extremity and adapted for alternate actuation by opposed sets of electro-magnets 20 and 21. One terminal of the coil of each electro-magnet 20 and 21 is connected by a ground wire 22 with the track rails 5-6.

Relatively short overhead conductors 24 are suspended from the hanger arms of the trolley poles 9 in adequately spaced relation upon each side of the road or highway crossing and are provided with upwardly curved ends to insure proper engagement of the auxiliary trolley wheel 25 carried by an arm 26 of the main trolley arm 11. The adjacent extremities of the overhead conductors 23 are connected by conductors 27 with the terminal of the coil of the electro-magnet 20 opposite the ground connection 22.

The equipment of the car consists, in addition to the auxiliary trolley arm and wheel of a manually operable switch 28 arranged within convenient reach of the operator of the car and having one of its poles connected by a conductor 29 with the conductor 14 whereby current from the main trolley wire 8 or 9, according to which track the car is traveling on, is conducted to one pole of the switch 28. The opposite pole of the switch 28 is connected by a conductor 30 with the auxiliary trolley wheel 25 whereby the latter is

energized when engaged with the trolley to close the circuit to the electro-magnet 20 and cause the operation of the signal bell.

An inner pair of conductors 32 and 33 is suspended from the hanger arms of the trolley poles 9 at points on opposite sides of the road or highway crossing and inwardly of the conductors 23 and 24 and the adjacent terminals of the conductors 32 and 33 are connected by conductors 34 and 35, respectively, with one pole of the motor 16, the opposite pole of the motor being connected directly with one of the rails of the railway track whereby to complete the electrical circuit to the motor 16 and consequently cause operation of the latter.

The conductors 34 and 35 are also connected with the terminal of the electro-magnet 21 opposite the ground connection 22 whereby the circuit to the magnet is closed simultaneously with the closure of the motor circuit.

The operation of the apparatus may be briefly stated as follows:

A car 10 approaching the road or highway crossing from the direction indicated in Fig. 1 engages its supplementary trolley wheel 25 with the conductor 24 thereby closing the circuit to the magnets 20 from the track rail 6 through the conductor 22, coil of the magnet 20, conductors 27 and 24, conductor 30, switch 28 and conductors 29 and 14 to the trolley or feed wire 8. The magnets 20 and 21, as will be understood, are provided with conventional types of circuit interrupters such as are ordinarily utilized in conventional types of buzzers and bells for producing a vibratory movement of the clapper arm 18 by which a rapid succession of warning sounds is produced. As the auxiliary trolley wheel 25 moves off of the terminal of the conductor 24 and passes through the space between the adjacent terminals of the conductors 24 and 32, the operation of the signal device 17 is momentarily discontinued but is promptly set in operation again upon contact of the auxiliary trolley wheel 25 with the inner conductor, the electro-magnet 21 being utilized in this instance to operate the signal and the circuit thereto being completed from the track rail 5 through the ground connection 22, coil of the magnet 21, conductors 34 and 32, auxiliary trolley wheel 25, conductor 30, switch 28 and conductors 29 and 14 to the trolley wire 8. Due to the connection of the motor 16 with the conductor 34 the circuit thereto is completed simultaneously with the closure of the circuit for the magnet 21 and consequently the motor is set in oper-

ation and, being connected with the railway gates 15 in the manner disclosed in my co-pending application results in the closure of said gates temporarily suspending traffic across the railway tracks until the approaching car has passed. As will be understood, the switch 28 is normally closed and is simply designed for utilization as when the car is compelled to stop to take on or discharge passengers or for any other reason at a point adjacent to the road or highway crossing. In such instances, the manual operation of the switch by the operator of the car permits the circuit to be opened resulting in the movement of the railway gates to open position and the resumption of traffic. However, when the car is prepared to proceed, the operator again closes the switch setting the alarm 17 in operation and reclosing the gates 15.

If preferred, the overhead conductors 23, 24, 32 and 33 may be dispensed with and instead of being arranged overhead may be arranged alongside of the track rails 5 as indicated at 24¹ and 32¹. Of course, if this type of the invention is adopted it will be found desirable to inclose those portions of the conductors which are exposed for the protection of life and property and instead of the overhead trolley wheel, a car carried shoe is substituted. However, in either form of the invention the car equipment and gate operating and signal circuits are identical and consequently these details have not been illustrated in Fig. 2.

What I claim is:

In an apparatus of the type described, the combination with an electric trolley system including a control circuit carried by the cars thereof, of motor operated gates arranged at highways crossing the tracks of said system, conductors arranged in sections parallel to the trolley wires of the system and extending for a distance on either side of the highway crossings, said conductors leading to and connecting the operating motor for said gates, an alarm circuit arranged adjacent to said gates and connecting said conductors for simultaneously operating with said gates, means carried by the cars of the system for closing the circuit between said conductors and the control circuit carried thereon, and a manually actuated switch carried by each car of the system for operating the control circuits substantially and for the purpose set forth.

In testimony whereof, I affix my signature hereto.

NICHOLAS P. THEOFILOS.
